UNITED STATES PATENT OFFICE.

WILHELM KUEHNER, OF PROVIDENCE, RHODE ISLAND.

DESIGN FOR A BRACELET OR SIMILAR ARTICLE.

Application filed May 19, 1928. Serial No. 26,757. Term of patent 7 years.

To all whom it may concern:

Be it known that I, WILHELM KUEHNER, a citizen of the United States, residing at Providence, in the county of Providence, and State of Rhode Island, have invented a new, original, and ornamental Design for a Bracelet or Similar Article, of which the following is a specification, reference being had to the accompanying drawings, forming part thereof.

The figure shown in the drawing is a perspective view of my new design for a bracelet, only a portion of the ornamentation of the bracelet being shown, but it is understood that the remainder is a mere repetition thereof.

I claim:

The ornamental design for a bracelet or similar article, as shown and described.

In testimony whereof I have signed my name to this specification.

WILHELM KUEHNER.
